UNITED STATES PATENT OFFICE

WILLIAM L. CALKINS, JR., OF FREEPORT, ILLINOIS

ADJUSTABLE DISPLAY RACK

Application filed May 13, 1929. Serial No. 362,488.

My invention relates to display stands of the type employed for displaying merchandise in retail stores and is particularly adapted to display merchandise of small size, such as groceries, vegetables, and fruit in store windows.

In order to utilize the space of display windows to the best advantage it has become customary for grocers, fruit dealers and the like, who deal in merchandise small of size, to construct a false floor or stand having sloping sides behind the window whereby the display is raised from the normal floor level and the merchandise placed along the inclined sides to present it more fully to the view of prospective purchasers. These stands have been permanent or semi-permanent in character and have been constructed separately for the particular window in which they are used. Alterations may be made in such a structure only with difficulty. It is, however, often desirable and advantageous to change the length or slope of these stands to better accommodate particular merchandise.

One of the objects, therefore, of my invention is the provision of a display stand adapted to be altered in length and in which the slope of the face may be varied within limits.

I have also aimed to provide a structure which may be easily assembled and dismantled whereby the same may be readily moved from place to place.

A still further object of my invention is the provision of a display stand wherein the arrangement of the display may be altered without disturbing the individual sections thereof.

Another object is the provision of a sectional stand adapted to be varied in size to accommodate different quantities of display materials.

I have also aimed to provide a structure of the character described which is economical to manufacture.

Other objects and advantages of my improved construction will become apparent from the following description and the accompanying drawings in which

Figure 1 is a perspective of the stand partly assembled;

Fig. 2 is a section on the line 2—2 of Fig. 1;

Fig. 3 is an end view of the rack showing the bottom flange in place, and

Fig. 4 is a section on the line 4—4 of Fig. 1, showing the slide construction.

The invention includes generally an adjustable frame or rack capable of being raised at one edge to various elevations, face members adapted to be positioned upon the frame, and shelf members arranged upon the face members.

Referring to the drawings, the frame includes end members 6 and side members 7. The end members 6 consist of a single piece slotted on their upper sides at 8 and 9 to provide a mortised joint with the side members 7 and attached to bases 10 at their lower ends by means of hinges 11. Bottom flanges 12 and 13 are attached to the lower ends of the end pieces 6 by means of bolts or dowel pins 14.

The side members 7 each consist of two parts, a grooved part 15 and a tongued part 16 as shown more fully in Fig. 4. The tongued part 16 may preferably be made of metal of U-shaped cross-section and have the edges turned in to form tongues 17 cooperable with grooves 18 of the grooved part 15 to form a slidable connection. At their free ends each of these parts are mortised into one of the cross pieces 6 at points 8 and 9 whereby a rectangular frame is formed. I have found it convenient to remove complementary portions of the material of each member to form a removable mortised joint which is cheaply made yet permits the members to be easily set up or taken down by merely lifting one member out of the other.

The frame thus provided is arranged to be swung on the hinges 11 about a horizontal axis to provide different degrees of angularity with respect to the base 10. Supporting arms 19 are pivotally connected to the underside of the cross members 6 by means of hinges 20, the lower ends of the supporting arms being adapted to be positioned in any one of a series of recesses 21 in each of the bases to support the frame in the desired de-

gree of angularity with respect thereto. Because of the slideable connection between parts 15 and 16 the frame is also adjustable as to length, the frame being shortest when the 5 inner ends of the bottom flanges 12 and 13 are in contact and longest when the parts 15 and 16 are extended upon each other to the greatest practical extent.

Two types of facing members are employed, those of the type indicated in the drawings by the numerals 22, 23, and 24, adapted to be positioned at each end of the frame over flanges 12 and 13, and those of the type indicated by 25. The former consist of wood or metal slabs of convenient width and thickness long enough to extend across the frame and permit a portion to project over the side members thereof. The facing members of the type indicated by 25 are 10 extra members adapted to be inserted at the center when the frame is extended and are similar to the others except for a vertical portion 26 equal in height and thickness to bottom flanges 12 and 13 designed to act as 15 an extension thereof. Each of the facing members are provided with brackets 27 attached to the rear side thereof near the bottom end in a position to engage the upper edge of the lower side member 7 whereby the 20 facing member is, by its weight, positioned upon the frame. Openings 28 are provided in each of the facing members, suitably positioned to cooperate with tongues 29 attached to shelves 30 or trays 31 in supporting said shelves at a plurality of positions.

The shelves, which may be in the form of trays as at 31, boxes, or baskets have a tongue or tongues 29 attached to their bottom and projecting outward therefrom, the outer ends of the tongues being bent downward as 40 shown at 32 whereby the angularity of the shelves with respect to the facing members may be altered by altering the distance the tongues are inserted into the openings 28.

A shelf 35 may be provided at the upper end of the facing members extending backward therefrom if desired by attaching brackets 33 to the rear of said facing members near the upper end. Tongues 34 attached to the shelf and having their outer ends bent downward may be inserted behind 50 said brackets to support the shelf thereon.

The advantages of my improved construction will be readily apparent to those skilled in the art. A fruit dealer opening a store will no longer be required to call in a carpenter or tinsmith to install a display stand for his window or store for my construction may be installed therein because of its adjustability. The degree of angularity, of the shelves with respect to the facing members placed on the frame may be varied, and the length of the stand itself may be varied. The shelves may be moved from position to

position without disturbing the arrangement of the merchandise on the shelves.

It will be evident that the stand may be made from any suitable material such as metal or wood or combinations of the two 70 and may be very readily put up or taken down by any person of normal intelligence, whereby the stand may be easily moved or stored for subsequent use without damaging the structure as occurs when the parts are 75 permanently fastened together as by nails.

While I have thus described and illustrated a particular embodiment of my invention, I am aware that numerous changes may be made without departing from the spirit of 80 the invention or the scope of the appended claims, in which—

I claim:

1. A display stand comprising a frame having base members, a rack comprising cross members, and extensible side members connecting the ends of said cross members, and means for supporting the latter at different degrees of angularity with respect to the former, facing members having openings 85 therein arranged to be positioned upon said frame to form a continuous surface over said frame, bottom flanges positioned at the lower ends of said facing members to form a supporting projection, and shelves arranged to 90 be positioned one above another on the inclined face of said facing members to permit horizontal rows of vertically spaced displays, each having at least one tongue attached thereto adapted to be inserted in any 95 of said openings, said tongues being shaped to support said shelves upon the facing members at any one of a plurality of angles, dependent upon the angularity of said rack with respect to said base members, to support said shelves in a horizontal position.

2. A display stand comprising a frame having base members, a rack comprising cross members, and extensible side members connecting the ends of said cross members, and means for supporting the latter at different degrees of angularity with respect to the former, facing members having openings 110 therein arranged to be positioned upon said frame to form a continuous surface over said frame, bottom flanges positioned at the lower end of said facing members to form a supporting projection for material to be displayed, shelves arranged to be positioned one above another on the inclined face of said facing members to permit horizontal rows of vertical disposed displays, each having at least one tongue attached thereto adapted to be inserted in any of said openings, said 115 tongues being shaped to support said shelves upon the facing members at any one of a plurality of angles, dependent upon the angularity of said rack with respect to said base members, to support said shelves in a horizontal position, brackets attached to the rear 120

of said facing members, near the upper ends, and at least one shelf having at least one tongue attached thereto adapted to engage said bracket for supporting said last named shelf behind the facing members.

6 In witness of the foregoing I affix my signature.

WILLIAM L. CALKINS, JR.
